ALBERT M. CANDY, OF WILKINSBURG, PENNSYLVANIA, ASSIGNOR TO WESTINGHOUSE ELECTRIC & MANUFACTURING COMPANY, A CORPORATION OF PENNSYLVANIA

METHOD OF WELDING

Application filed November 1, 1926. Serial No. 145,481.

My invention relates to building construction and especially to improvements for interlocking a column or upright with a girder or beam engaging therewith.

5 An object of my invention is to improve both the method of joining beams and the finished joint between beams, to effect savings in the time employed and the cost of material.

Another object of my invention is to interlock welded beam and column members by 10 inserting what I call "continuity plates" between the flanges of the column member to form a continuation of the flanges of the beam or girder member, the advantages of 15 such continuity plates being peculiar to welded constructions wherein the parts are molecularly integral.

A further object of my invention is to strengthen the web members of the joint to 20 the end that the full strength of the column and beam sections may be developed.

It is customary, in the assembly of structural steel parts, to unite beam and column members by means of angle irons riveted 25 thereto. However, under the condition of heavy loading it has been found that the angle iron forming the joint is subjected to a bending moment which tends either to close or to open up the angle member, depending on its 30 position in the joint.

The disengagement of the abutting members resulting from a partial or complete buckling of the angle irons causes a serious 35 loss in joint rigidity as well as an inefficient utilization of the material in the affected structural members.

Attempts have been made to overcome the above-mentioned objections by devising means for interlocking the riveted members. 40 All such structures, however, have proved either too costly or too cumbersome to warrant their adoption, except for the occasional prevention of swaying in tall buildings.

The provision of rivet holes in skeleton 45 steel structures obviously reduces the effective cross section of the beams and impairs their total strength. In consequence, the design of such structures requires the use of girders of sufficient strength, at the riveted or weakest section, to resist the stresses for which it

is designed, while the portions of the beam where there are no joints are of excessive strength for the purpose contemplated. As a consequence, all of the members of riveted steel structures do not work at their full capacity. 55

My invention relates to methods of, and means for, overcoming the foregoing and other difficulties heretofore experienced by the skilled workers of the art, as will be more 60 particularly pointed out in the following detailed description and in the claims appended hereto, reference being made to the accompanying drawings, wherein

Figure 1 is a perspective view of a butt 65 welded beam-column joint;

Fig. 2 is a perspective view of the construction shown in Fig. 1 after it has been loaded to failure;

Fig. 3 is a section taken on the line III—III 70 of Fig. 2;

Fig. 4 is a perspective view of my improved welded and reinforced joint construction;

Fig. 5 is a perspective view of my joint construction shown in Fig. 4 after the members 75 have been loaded to failure; and

Fig. 6 is a section taken on the line VI—VI of Fig. 5.

In the embodiment of my invention shown in the drawing, my new means of reinforcement, which I call "continuity plates" are shown at 1 and 2, in Fig. 4, the said plates being fillet welded to the flanges 3 and 4 and to the web 5 of an H-beam column 6. The continuity plates just mentioned are disposed in the same planes as the respective top and bottom flanges 7, 8 and 9, 10 of the horizontal beams 11 and 12, which are welded in abutting engagement against the side flanges 3 and 4 of the column 6. 80

While the drawings show only the continuity plates 1 and 2 which are in front of the central web 5 of the column 6, it will be understood that other continuity plates (not shown) are welded to the opposite sides of 95 the web 5 and to the flanges 3 and 4, in the planes of the flanges 7, 8 and 9, 10. The continuity plates 1, 2 and the beams 11 and 12 are united with the web and flanges of the column 6 to form an integral unit by arc- 100

welding the abutting edges in a manner well known in the art.

On the application of a load to the beams of the structure shown in Fig. 4, the stresses in the beam flanges are transferred directly to the column member without the development of such bending moments as would tend to cause distortion of the column. The continuity plates, therefore, serve as reinforcements for the web member and also as rigid ties between the flanges of the column.

When a structure of the type just described is tested to destruction, failure occurs by the gradual and extended distortion of the horizontal beam members, as illustrated in Figs. 5 and 6, showing that the welded joint is stronger than the other parts of the structure.

The performance of a structural steel unit according to my invention contrasts with the failure of riveted constructions, where an actual shearing of the rivets and a tearing of the angle-irons causes a premature failure of the joint before the limit of strength of the rest of the structure is reached.

To avoid the objectionable characteristics of riveted structures, it has been proposed, in the past, to weld abutting beam and column members together. The welded joints of the prior art, as shown in Figs. 1, 2 and 3, differ from my improved joint in omitting my continuity plates 1 and 2.

Joints that I have prepared in the old manner, shown in Figs. 1, 2 and 3, have been found to possess increased rigidity and carrying power over that obtained with riveted designs, because of the fact that, in riveted construction, the clearance usually allowed in the rivet holes and the flexure of the metal of the angle plate will prevent the abutting flanges from fully contributing to the strength of the joint. In the welded construction, however, the abutting flanges form an integral unit with the column, and a materially increased stiffening is the result.

I have found that, when such welded structures of the prior art are subjected to destructive loads, failure ultimately occurs by the buckling of the web section of the column, as indicated in Figs. 2 and 3, so that, even in this construction, the joint is not sufficiently rigid to achieve the desired efficient utilization of the main portions of the beam members.

A demonstration of the relative merits of the old and new designs shown in Figs. 1 and 4, respectively, was made at the Carnegie Institute of Technology, Pittsburgh, Pa., on July 28, 1926, before a group of contractors, architects and engineers. The H columns used were 8 inches deep, 32 pounds per foot, 2 feet high, while the Bethlehem I beams were 9 inches deep, 20.5 pounds per foot, 3 feet long. The continuity plates utilized in the new design were 6 $\frac{5}{8}$ " long, 3"

wide and 5 $\frac{1}{8}$ " thick. For test purposes, a compression load was applied to the column with the beams supported on blocks spaced 6' 2 $\frac{1}{2}$ " apart.

The new structure shown in Fig. 4, employing continuity plates in accordance with my invention, failed at a loading of 70,000 pounds, whereas the structure without the continuity plates failed at a loading of 50,000 pounds showing that a 40% increase in strength was obtained by employing my four small continuity plates.

No distortion of the joint was apparent in the structure having continuity plates, failure occurring by the twisting of the web of the horizontal beam members, substantially as shown in Figs. 5 and 6. However, in the case of the joint in which continuity plates were not used, failure occurred in the joint section, by the buckling of the web of the vertical column, substantially as shown in Figs. 2 and 3. By the use of continuity plates I am able, therefore, to secure a joint between structural members of such a nature that any part thereof is stronger than the individual members.

Although I have described a specific embodiment of my invention, it is apparent that various changes may be made within the scope thereof without departing from the principles herein set forth.

For instance, while the construction that I have shown relates to a single column or upright having several beams or girders attached in abutting engagement therewith, my invention may be applied, with equal effectiveness, to an oppositely disposed column or upright and to the opposite end of a connecting girder or beam.

Furthermore, while I have illustrated the principles of my invention as applied to a stress-transfer from the flanges of H and I beams, it is to be understood that the beams employed are by no means limited to the shapes just mentioned, and the expression "flanged-means" in some of the appended claims is intended to designate generically any usual structural beam, including H and I beams, channel irons, angle and T irons. Similarly, when I refer, for convenience in expression, to columns and horizontal beams, I refer only to the relative positions of the several parts with respect to each other and to the loads carried thereby, which are assumed to be in a vertical direction, as it is obvious that I am not limited to any particular inclination with reference to the direction of gravity.

I claim as my invention:

1. A metallic-joint construction comprising an upright provided with vertical flanges and a connecting web and a beam abutting one of said flanges provided with horizontal flanges and a connecting web, a fillet weld connection between said beam and said up-

right along the edges of the contacting portions thereof, reinforcing members extending between said vertical flanges in alignment with said horizontal flanges and a fillet-weld connection between said upright and the contacting edges of said reinforcing members.

5 2. In building construction, a plurality of metallic flanged beams, portions of two or more of said beams having mutual surface-contacting portions joined along the edge of said contacting portions and a plurality of reinforcing members inserted between the flanges of one of said beams and welded thereto in alignment with the flanges of the 10 abutting beams whereby the reinforcing members will oppose the distortion of the beam in which they are mounted whether they are subjected to compressive or tensile 15 stresses.

20 3. In a metallic-joint construction, an angle-sectioned beam comprising a web having a flange at one side thereof, a second angle-sectional beam comprising a web having a flange at each side thereof, said second beam 25 abutting the face of the flange of said first beam, with the webs of the two beams in the same plane, a tension plate and a compression plate disposed in the angle of the first beam between the web and the flange thereof, 30 the said tension plate being in substantial alignment with one flange of the second beam, and the said compression plate being in substantial alignment with the other flange of the second beam, and welded joints integrally uniting the several contacting parts.

35 4. The combination with an upright having a vertical web portion and two vertical flanges at the sides thereof, of two horizontal beams abutting against the outer surfaces of 40 the two flanges of the upright and integrally joined thereto, said beams lying in substantially the same horizontal plane and each comprising a vertical web portion and top and bottom horizontal flanges, and one or 45 more tension plates interposed between the flanges of said upright and integrally united to said flanges of the upright in substantially the plane of the top flanges of the said horizontal beams, and one or more compression 50 plates interposed between the flanges of said upright and integrally united to said flanges of the upright in substantially the plane of the lower flanges of the said horizontal members.

55 In testimony whereof, I have hereunto subscribed my name this 26th day of October, 1926.

ALBERT M. CANDY.
